UNITED STATES PATENT OFFICE.

CHAUNCEY MATLOCK, OF NEW YORK, N. Y., ASSIGNOR TO GASOLINE CORPORATION, OF NEW YORK, N. Y., A CORPORATION OF DELAWARE.

PROCESS AND APPARATUS FOR TREATING HYDROCARBON OILS.

Application filed September 27, 1920. Serial No. 413,020.

This invention relates to a process and apparatus for treating hydrocarbon oils and more particularly to a process and apparatus for treating the products obtained in continuous processes of cracking heavy hydrocarbon oils for the production of lighter hydrocarbons.

In cracking processes of the continuous type, in which the oil undergoing treatment is passed in a continuous stream through a heating coil or other heating means and is heated to, and maintained at, a temperature sufficient to crack a substantial portion of said oil, a variety of hydrocarbon products is formed which range from light permanent gases, which do not condense at ordinary temperatures, to heavy products which do not readily vaporize at very high temperatures. If the product thus obtained is condensed, a mixture of hydrocarbons, resembling crude petroleum in boiling point range and in many other physical characteristics is obtained. The mixture of hydrocarbons obtained in this manner may be fractionally distilled in the same manner as natural crude petroleum to separate it into the desired fractions. In condensing and redistilling the products, however, a comparatively large quantity of cooling water and heat is used and moreover a large amount of equipment is necessary for carrying on the various distillations.

An object of the present invention is to provide a process, by which the products obtained in cracking hydrocarbons, may be separated directly into a number of fractions of different boiling point limits.

Another object of the invention is to provide an apparatus by which the products obtained in the continuous cracking of hydrocarbon oils may be continuously separated in a single operation into fractions of different boiling point limits.

Of the heavier hydrocarbons resulting from the cracking operation remaining after the separation of the lighter products suitable for gasoline, those products having a boiling point next above the gasoline fraction and corresponding in boiling point range to the material originally used, may be resubjected to the cracking operation for the production of additional quantities of gasoline. The heavy hydrocarbons condensing only at temperatures above this intermediate

fraction are, however, not suitable for re-cracking, since they contain a very high carbon content and upon cracking cause trouble from the excessive formation of carbon. It is, therefore, more profitable to sell this heavy fraction as fuel oil or other type of heavy hydrocarbon product.

A further object of the invention is to provide a process and an apparatus for treating hydrocarbon oils to produce lighter hydrocarbons in which those products suitable for rerunning are continuously separated from the heavier and lighter hydrocarbons and are returned to the cracking operation.

With these and other objects in view, the invention consists in the process and apparatus described in the following specification and defined in the claims.

The various features of the invention are illustrated in the accompanying drawings, in which

Fig. 1 is a diagrammatic sectional elevation of an oil cracking plant and dephlegmator embodying the preferred form of the invention, and

Fig. 2 is a sectional elevation of the dephlegmator shown in Figure 1.

In the preferred embodiment of the present invention, the oil to be cracked or transformed into light hydrocarbon liquids is mixed with a small quantity of steam and passed in a rapid, continuous stream through coils of pipe heated in a furnace to a cracking temperature. The operation of this part of the process is substantially the same as described in the Greenstreet Patent, No. 1,110,924 the steam serving to prevent the deposition of carbon on the inner walls of the coil. The cracked vapors pass from the heated coils directly into a cooling header or chamber into which a number of jets of water or cooling fluid are injected, and the vapors are rapidly chilled by evaporation of the jets of water to a temperature at which further cracking of the vapors ceases. The vapors pass from the cooling header through a pressure release valve into the lower part of a dephlegmator which serves to separate the vapors into a number of sharply defined fractions.

As the vapors enter the lower part of the dephlegmator, they are further chilled by a spray of water which is injected into

the vapors in sufficient amount to bring the vapors uniformly to a definite temperature. A mist of condensed particles containing substantially all hydrocarbons having a boiling point above the temperature maintained in the lower part of the dephlegmator is immediately formed. As the vapors pass upwardly through the dephlegmator the condensed particles are separated from the vapors by a number of baffle plates. The vapors freed from the mist of condensate pass upwardly through the dephlegmator, and are again chilled to a lower temperature by a second jet of liquid which is injected in an amount sufficient to cool the vapors to the higher boiling point limit or "end point" of the light distillate desired or of an intermediate fraction as may be the case. The mist formed by this second chilling contains those vapors which condense between the temperature limits established by the first and second cooling jet mentioned above. The suspended particles forming this mist are maintained in suspension in the gases at a fixed zone by a balance between the force of gravity and the frictional resistance between the gases and particles of condensate. A small quantity of gas is continuously withdrawn from the dephlegmator adjacent the zone in which the particles are suspended and carries with it the accumulation of condensate formed during the process. The gases passing upwardly through the dephlegmator are freed from any particles of condensate which might be carried upwardly and may be again subjected to a cooling spray or may leave the dephlegmator and enter a condenser.

Referring to Figure 1 of the accompanying drawings, a supply of oil or other hydrocarbon to be treated is drawn from a supply tank, not shown, through a supply pipe 10 and forced by means of a pump 12 through a delivery pipe 14 leading to the cracking coils. The oil delivered to the pipe 14 is distributed to a number of coils through branch pipes 16, the quantity of oil passing to each coil being measured by means of meters 18 and controlled by means of valves 20 in the pipes 16. Before entering the cracking coils, the oil is mixed with a quantity of steam supplied from a header 22 through branch pipes 24 and controlling valves 26. The mixture of steam and oil under pressure passes through pipes 28 to cracking coils 30 maintained at a cracking temperature in a furnace 32. The oil is vaporized and cracked in passing through the coils 30, and the cracked vapors are conducted from the coils 30 through connecting pipes 34 to a cooling header 36 in which they are immediately chilled by the evaporation of jets of cooling water or other liquid injected through inlet pipes 37 into

direct contact with the vapors. The chilled vapors pass from the cooling header 36 through a delivery pipe 38 and a pressure valve 40 to the lower part of a dephlegmator column or chamber 42 shown in detail in Fig. 2 of the drawings.

The partly chilled vapors entering the dephlegmator 42 through the pipe 38 are received in a chamber 44, Fig. 2 in the lower part of the dephlegmator. In the chamber 44 the vapors are further cooled by a jet of water entering the chamber through a pipe 46 and sprayed into the vapors through a nozzle 47. The water is divided by the nozzle 47 into a very large number of very small drops or particles which are dispersed uniformly throughout the upwardly passing hot vapors. A comparatively very large surface of contact is, thereby, obtained between the hot vapors and the liquid particles, which accordingly evaporate substantially instantaneously into the vapors. This evaporation absorbs a large quantity of heat and chills the vapors throughout to a definite temperature. The temperature of the vapors is measured by means of a pyrometer 48 and the quantity of water injected is adjusted to bring the temperature to a definite point. In the sudden chilling of the vapors the heavier hydrocarbons are condensed throughout the vapors and form a mist or suspension, the formation of the mist being apparently facilitated by the presence of the small drops of water, which appear to form nuclei for the building up of the condensed particles and favor the formation of substantially uniform drops or particles of condensate throughout the vapors.

From the chamber 44 the vapors pass upwardly through an opening 50 in the center of a baffle 52 which extends across the dephlegmator and flow outwardly to the edge of a second baffle plate 54 and upwardly through a passage 56 between the edge of the baffle 54 and the dephlegmator walls. From the passage 56 the vapors pass over the baffle plate 54 and upwardly through an opening 60 in a higher baffle plate 62 into a chamber 64. In passing back and forth between the baffles 52, 56 and 62, the suspended particles of condensate impinge on the walls of the baffles and the inner wall 58 of the dephlegmator and are separated from the upwardly passing vapors and gases. From the chamber 64, the gases and vapors pass upwardly through the baffles 66, 68, and 70 arranged similarly to the baffles 52, 56, and 62 in which any further particles of liquid condensates are separated from the gases and vapors.

After passing through the baffle 70 the gases are received into a chamber 72 into which a second supply of cooling water is injected through an inlet pipe 74 and sprayed into the upwardly passing vapors.

The temperature of the gases and vapors in the chamber 72 is measured by means of a pyrometer 76, and the quantity of water entering the pipe 74 is adjusted by means of a valve 78 to maintain a definite temperature in the chamber 72. The temperature in the chamber 72 is maintained at approximately the temperature of the upper end point of the light hydrocarbon liquid to be produced in the process. Those hydrocarbons having boiling points higher than the temperature maintained in the chamber 72 and lower than that maintained in the chamber 44, are therefore condensed and form a mist of condensed particles in the chamber 72.

The velocity of passage of the gases upwardly through the chamber 72 is so controlled as to obtain a balance between the force of gravity tending to cause the particles of condensates to fall and the lifting force of the upwardly passing gases, and to thereby hold the suspended particles substantially stationary in the zone or chamber 72. The tendency of the particles to rise may be further lessened through the decrease in volume of the gases due to the condensation of the hydrocarbons, and the consequent decrease in velocity of the gases after leaving the condensing zone. This balance between the lifting and lowering forces on the condensed particles causes the suspended particles to accumulate in the chamber 72. The accumulation of suspended particles is continuously removed from the chamber by withdrawing a small quantity of the upwardly passing gases through an outlet opening 80, in the side of the dephlegmator. The proportion of gases withdrawn through the opening 80 is comparatively small as compared with the volume passing upwardly through the dephlegmator, since a much greater velocity must be maintained in an upward direction to sustain the particles against the force of gravity than to draw them through the opening 80 in which their passage is not opposed by any force.

To prevent any of the suspended particles from being carried upwardly with the gas, the gas is passed through a number of baffles 82, 84, 86, 88, 90, 92, 94, 96 and 98 arranged similarly to the baffles 52 to 70. After passing through the uppermost baffle 98, the vapors free from the condensates and containing only the vapors condensable below the temperature maintained in the chamber 72, together with steam and incondensable gases, are received in an uppermost chamber 100. The gases and vapors are withdrawn from the chamber 100 through an outlet pipe 102 and pass through a vapor pipe 104 to a condenser 106, in which the light vapors are condensed.

The heavy condensates which are caught on the baffles 52 and flow downwardly through a number of overflow pipes 108,

110, 112, 116 and 118 to the bottom of the dephlegmator. The overflow pipes are, of course, so arranged as to maintain a slight amount of condensate on each baffle plate. The liquid flowing down through the overflow pipe 118 collects in the chamber 44 until it reaches the level of an outflow pipe 120 from which it is drawn through a cooler or condenser to a fuel oil storage tank not shown. Similarly, the liquid collecting on the baffles 82 to 98 flows downwardly through overflow pipes 122 to the baffle 70. As these condensates, however, flow downwardly over the baffles 70, 68, 66, 56, and 52, they are reevaporated and carried upwardly with the upwardly passing vapors and again brought into the chamber 72 and recondensed.

The mixture of suspended condensate and gases withdrawn through the outlet pipe 80 passes into a condenser or separator in which the condensed particles are collected and removed to a run down tank or to the oil supply tank. This condensate is similar in boiling point range and composition to the hydrocarbons which are supplied to the process through the pipe 10 and may, therefore, be returned, together with additional supplies of oils to the cracking process.

In the description of the process given above, water has been indicated as the cooling fluid, in the different temperature zones. The invention is not, however, limited to the use of water as a cooling fluid and any fluid capable of maintaining the desired temperature may be substituted for water. In some cases it may be desirable to use certain types of crude petroleum or petroleum distillates, in which case a fractionation or purification of the petroleum distillate may be obtained. Ordinarily, however, water is used as it is more easily controlled in the type of apparatus described. In the above described apparatus only three fractions are obtained, but the number of fractions may be increased by inserting a number of jet pipes and connecting a number of draw-off pipes, similar to pipe 80, to the chamber 64 and to the spaces between baffles 86 and 88 and 92 and 94.

The dephlegmator is provided with a draw-off pipe 122 at its lower end, and with a removable cover 124 through which access may be had to the upper part of the tower, for purposes of cleaning and repair. A derrick or angle 126 is provided at the top of the dephlegmator for removing the baffles 52 to 98 in cleaning and repairing the apparatus. Each of the baffles 54, 68, 84, 90 and 96 is provided with rings 128, 130, 132, 134, 136 respectively, which may be engaged by a hook suspended from the scaffold 126 by tackle blocks or pulleys or other suitable hoisting means. The baffles are connected in sets of three so that upon lift-

ing the baffles 54, 68, 84, 90 and 96 the baffles immediately above and below are lifted at the same time.

While the invention has been described in connection with a particular type of oil cracking process it will be understood that it may be applied to other processes and to products than those described above.

Having described the invention what is claimed as new is:

1. A method of fractionating mixtures of vapors of varying boiling points, which comprises condensing and removing the highest boiling fraction from said vapors, passing the remaining vapors upwardly, injecting a cooling fluid into said upwardly passing vapors in amount sufficient to condense an intermediate fraction and form a suspension of said fraction in said vapors, maintaining the velocity of said gases at such a rate as to hold the suspension within a fixed zone, withdrawing said suspension and a portion of said gases from said zone, removing any suspended particles carried upwardly from said zone, returning said particles to the vapors below said zone, and removing and condensing the vapors separated from said intermediate condensate.

2. A method of fractionating vapors of different boiling points, which comprises injecting a cooling fluid into, and forming a suspension of high boiling condensates in, said vapors, separating said suspended condensate, passing said vapors upwardly, injecting a liquid spray into said vapors and condensing an intermediate fraction to form a suspension of said fraction in said vapors, maintaining the suspension of intermediate fraction in a fixed zone, withdrawing a portion of the gases and suspended particles from said zone, removing particles of suspended condensate from gases leaving said zone, and removing and condensing said residual vapors.

3. In a method of fractionating vapors of different boiling points, the step which comprises injecting a spray of cooling liquid into a moving stream of said vapors, and diverting a mixture of condensed particles and vapors from said stream in a direction different from the general direction of movement of said vapors.

4. In a method of fractionating vapors of different boiling points, the step which comprises suddenly chilling said vapors to a substantially uniform temperature within temperature limits, forming a suspension of condensed vapors within said temperature limits, and diverting said suspension of condensed vapors.

5. A method of fractionating vapors of different boiling points which comprises condensing and removing from said vapors constituents having boiling points above a temperature limit, chilling said vapors

throughout to a lower temperature and forming a suspension of intermediate condensates in said vapors, maintaining the velocity of said vapors at a rate to maintain said suspension within a definite zone, withdrawing a portion of said vapors and said suspension from said zone, freeing said upwardly passing vapors from said suspension, and condensing said vapors.

6. In a method of fractionating vapors of different boiling points, the steps of spraying liquid into an upwardly moving stream of vapors, maintaining the velocity of the vapors sufficient to hold a mist of condensed particles within a definite zone, and withdrawing said suspended particles across the path of said gases and vapors.

7. An apparatus for fractionating vapors of different boiling points which comprises an upright column, means for spraying a cooling liquid into the lower part of said column, baffling means above said spraying means, means for spraying a cooling liquid into said column above said baffling means, an outlet from said column adjacent said last mentioned spraying means, additional baffling means above said outlet, means for returning liquid from said baffling means to the lower part of said column, and an outlet from the upper part of said column.

8. In an apparatus for treating hydrocarbon oils the combination of a furnace, pipes in said furnace, means for supplying fluids to said pipes, a cooling header connected to the outlet ends of said pipes, means for injecting liquid into said header, an upright chamber connected near its lower end to said header, means for spraying liquid into said chamber at different heights, outlet pipes adjacent said liquid spraying means, and baffles positioned between said liquid spraying means.

9. In an apparatus for treating hydrocarbon oils the combination of a furnace, a number of pipes in said furnace, means for supplying fluids to said pipes, a cooling header connected to the outlet end of said pipes, means for spraying liquid into said cooling header, a dephlegmator connected to said cooling header and a pressure release valve between said cooling header and said dephlegmator.

10. In an apparatus for treating hydrocarbon oils the combination of a furnace, a number of treating pipes in said furnace, means for supplying fluids to said pipes, a header connected to the outlet ends of said pipes, a means for injecting liquid into said header, and means for fractionating the vapors thus cooled.

11. An apparatus of the class described comprising means for cracking hydrocarbon oils, means for condensing the heavy fraction from the resulting mixture of hot vapors, means for forming a mist consisting

of condensed particles of an intermediate fraction suspended in uncondensed vapors, means for diverting a portion of said mist, means for condensing the intermediate fraction from the diverted portion of said mist and returning said condensate to the cracking means for rerunning, means for separating the intermediate fraction from that portion of the mist which is not diverted, and

10 means for revaporizing such condensate and returning it to said mist, and means for removing the uncondensed gases and condensed vapors having boiling points below that of the intermediate fraction for

15 further condensation and separation.

12. An apparatus of the type described comprising means for cracking hydrocarbon oils, a fractionating column into which the resulting mixture of hot vapors is directed,

means in the lower part of said column for condensing the heavy fraction from said mixture of hot vapors, means in said column for forming and maintaining a mist consisting of condensed particles of an intermediate fraction suspended in uncondensed vapors, means for diverting a portion of said mist, means for separating the condensed intermediate fraction from those portions of the mist passing into the upper part of said column, means for returning such condensate to the lower part of the column, and means for carrying off the uncondensed vapors having a boiling point below that of the intermediate fraction for further condensation and separation.

In testimony whereof, I affix my signature.

CHAUNCEY MATLOCK.
